UNITED STATES PATENT OFFICE.

ELIAS ROCKOFF, OF CHICAGO, ILLINOIS, ASSIGNOR OF ONE-HALF TO BERNARD ROCKOFF, OF CHICAGO, ILLINOIS.

STEM FOR ELECTRIC-LIGHTING FIXTURES.

1,423,683.

Specification of Letters Patent. Patented July 25, 1922.

Application filed July 6, 1920. Serial No. 394,206.

To all whom it may concern:

Be it known that I, ELIAS ROCKOFF, a citizen of the United States, residing at Chicago, in the county of Cook and State of Illinois, have invented a certain new and useful Improvement in Stems for Electric-Lighting Fixtures, of which the following is a full, clear, concise, and exact description, reference being had to the accompanying drawings, forming a part of this specification.

This invention relates to lighting fixtures, and has reference more particularly to pendant stems or wall brackets therefor. The invention has among its various objects the production of a stem which is simple in construction, cheap to manufacture, and which may be either stamped into form or cast of metal or other suitable material, and provided with the desired structure to facilitate the passage and retention of the conductors in their proper position relative to the stem and also to provide a means whereby various fixtures, such as globes, lights, etc., may be suspended therefrom or supported thereby.

The invention contemplates a structure which provides a separate groove or passage for each conductor thereby separating them, which permits each conductor to be inserted and passed along without interference.

The invention also contemplates an arrangement whereby the conductors may be enclosed or encased so as to conform with the fire ordinance or requirements of various cities and to present a more pleasing appearance when the stem is exposed to view, it being ordinarily hidden by a canopy which surrounds it. The invention has these and other objects, all of which will be more readily understood when read in conjunction with the accompanying drawing in which—

Fig. 1 is a sectional view of a stem applied in position.

Fig. 2 is a perspective view thereof.

Fig. 3 is a section taken on line 3—3 of Fig. 1.

Figs. 4, 5 and 6 illustrate modified structures which may be utilized at the lowermost end of the stem.

In the exemplification of the invention illustrated in the drawings the stem 10 is provided with a threaded extension 11 whereby it may be attached to the member 12 which is in turn connected to the extension 13 usually provided in buildings for the

purpose of affording a support to which lighting fixtures may be attached.

The opposite end of the stem is in this instance provided with an integral ring 14 to which is attached the usual globe or bowl 15 supports of the lighting fixture. This ring may be supplied with an arrangement whereby various attachments may be connected thereto, such as sockets, etc., and will be explained in detail in the following.

The invention has as an object the provision of an arrangement whereby each conductor may be readily inserted into, passed along and confined in a separate groove provided in the stem. This arrangement facilitates the passage of the conductors along the stem as the individual conductors are separated from each other by a wall which prevents their being brought into contact with each other. By separating the conductors and providing a separate groove or recess for each conductor instead of arranging two conductors in a single tube or passage, the conductors may be drawn through or passed along the recess with comparative ease as the usual friction between them and the stem is practically entirely eliminated.

These grooves are designated by the numerals 14^a and 15; are separated by the wall 10^a and extend along the stem from adjacent the uppermost end to near the opposite end where they terminate in a connection with a tubular opening 16 which is in alignment with its respective groove 14^a and 15. The uppermost end of each of these grooves 14^a is provided with a curved wall 17 which assists in guiding the conductor into and along the groove and through the opening 16.

The uppermost end of the stem is further provided with a transverse strap 18 which extends across the groove; this strap is provided to properly hold the conductors within the groove when a pulling strain is exerted thereon.

Provision for enclosing the conductors in the grooves is also made, the arrangement of this structure being such that it can be readily attached or removed as required. This structure includes a pair of plates 19, one for each groove, which is removably attached to the stem and extends from that end having the tubular apertures 16 to adjacent the straps 18. One edge of these plates is bent to produce the rib or flange 20

which is arranged in a groove 21 provided in the stem, the opposite edge of the plate is provided with an aperture through which the screw 22 is passed and then threaded into 5 the threaded opening 23 provided in the stem.

The ring 14 may be constructed so as to accommodate or have attached thereto various elements, such as a lamp socket or other 10 device, and to permit the conductors which extend from the stem to be passed therethrough to the element or device attached to the ring.

In the structure illustrated in Fig. 4 the 15 ring is provided with an internally threaded boss 24 into which may be threaded the threaded extension of a lamp socket or shell or any other device.

The structure shown in Fig. 5 shows a 20 ring provided with an externally threaded portion upon which may be threaded an internally threaded portion.

Whereas these extensions are shown as extending from the lowermost portion of the 25 ring, they may as shown in Fig. 6 be arranged so as to position the device sought to be attached so that it extends laterally with respect to the stem.

From the foregoing description it is obvious 30 that a simple and cheap structure is provided whereby the conductors may be readily threaded or passed along and properly retained in the grooves. It is also evident that by virtue of the straps 18 the conductors will be maintained in their proper 35 position so as not to interfere with the application of the plates 19 or the adjustment of the canopy along the stem.

What I claim and desire to cover by Letters Patent is—

1. A lighting fixture stem, one end of which is provided with means for securing said stem in position, the opposite end having a pair of apertures which are separated 45 by a wall which extends from said end to adjacent the opposite end of the stem, grooves arranged upon the opposite sides of the wall which separates said apertures, the opposite sides of said wall providing one 50 face of each of said grooves, a supporting member projecting from the opposite end of said stem whereby another supporting member may be secured to the stem, said last mentioned supporting member being arranged in substantial alignment with said 55 wall between the apertures provided at the lowermost end of the stem.

2. A lighting fixture stem, one end of which is provided with means for securing 60 said stem in position, the opposite end having a pair of apertures which are separated by a wall which extends from said end to adjacent the opposite end of the stem, grooves arranged upon the opposite sides 65 of the wall, the opposite sides of said wall

providing one face of each of said grooves, a strap arranged at the uppermost end of and extending across each groove, a supporting member projecting from the opposite end of said stem whereby another member may be secured to the stem, said last 70 mentioned supporting member being arranged in substantial alignment with said wall between the apertures provided at the lowermost end of the stem.

3. A device of the class described, comprising a stem, means provided at one end thereof whereby the same may be attached to a support and having means provided at the opposite end whereby an element may 80 be supported, said stem having a plurality of conductor receiving recesses and means for independently closing and exposing each recess, said means and stem having co-operating portions to hold said means with relation to the stem and said means being removable laterally with respect to the sides of the stem to expose said recesses.

4. A device of the class described, comprising a stem, means provided at one end thereof whereby the same may be attached to a support, a plurality of recesses provided in said stem, the uppermost end of said recesses being provided with means to assist in inserting a conductor therein, means provided at said end for retaining said conductor in the recess, the opposite end of the recess being closed by a wall having an aperture which is in substantial alignment with the recess and independently removable means for closing each recess, said means being removable laterally with respect to the sides of the stem to expose the recess, and means provided at the lowermost end of the stem for supporting another 100 element thereby said last mentioned means being arranged transversely to the apertures provided in the wall.

5. A device of the class described, comprising a stem, a threaded extension provided at one end whereby it may be attached to a support, said stem having a pair of separated grooves which extend substantially throughout the length of the stem for the reception of individual conductors, an aperture arranged at the opposite end of the stem at the lowermost termination of each groove, a closure for said grooves and a supporting member extending from the lowermost end of the stem, said supporting 110 member having threaded means whereby another member may be attached thereto.

6. A device of the class described, comprising a stem, said stem having parallelly arranged grooves for receiving conductors, the opposite end of the grooves having portions which extend transversely across each groove, one end of the stem having means whereby it may be attached to a support, and the opposite end having means ar- 125 130

ranged transversely to the grooves whereby another member may be supported thereby, said last mentioned transversely arranged means having an aperture to permit the 5 conductors to be passed therethrough.

7. A device of the class described, comprising a stem, said stem having parallelly arranged grooves for receiving conductors, the uppermost portion thereof being provided with a transversely arranged portion, one 10 end of said stem having means whereby it

may be attached to a support and having means provided at its opposite end and arranged transversely to the grooves whereby a member may be supported thereby said last mentioned means having a threaded aperture to permit the conductors to be passed therethrough and to permit another element to be secured to said stem.

In witness whereof, I hereunto subscribe my name this 30th day of June A. D., 1920.

ELIAS ROCKOFF.
